LOUIS V. LUCIA, OF ROME, NEW YORK, ASSIGNOR TO REVERE COPPER AND BRASS
INCORPORATED, A CORPORATION OF MARYLAND

PERCOLATOR PUMP

Application filed August 14, 1930. Serial No. 475,272.

This invention relates to percolators, and more particularly to the means for circulating the liquid therein.

According to a prevailing practice in electric percolator construction, an electrically-heated well is used, in which successive portions of the liquid are heated and forcibly discharged through the percolator tube communicating therewith. In conjunction with this well, some sort of control means is provided, to regulate the admission to the well of liquid to be heated and the subsequent building up of sufficient pressure to discharge the heated liquid through the percolator tube, and for this purpose, various types of valve control have been suggested.

The valve means which have been proposed, however, have presented various objections from the standpoints of mechanical construction and effectiveness of operation.

It is the object of my invention to provide a well structure in which the arrangement of parts and automatic control means are characterized by simplicity and accessibility of construction, certainty of operation, and the promotion of a highly effective circulation.

The manner in which I accomplish the same will be understood from the following description taken in conjunction with the accompanying drawing, in which

Fig. 1 is a vertical cross-section of the device of my invention, and

Fig. 2 is a horizontal cross-section taken along the line 2—2, Fig. 1.

Referring to the drawing, and in particular to Fig. 1, reference numeral 3 designates the percolator body or receptacle mounted upon a base 4 in any well known manner.

A heating and pumping well 5 is disposed within the receptacle 3, and is supported therein by connection with an annular electric heating unit 6 of suitable type which is mounted upon a pair of posts 7 in adjacent but spaced relationship to the bottom 8 of the receptacle 3, the posts 7 also serving as conduits for the lead wires to the heating unit.

The cylindrical body portion 9 of the well 5 may be formed integrally with the heat-

ing unit casing 11, or it may consist of a separate section closely connected to the casing 11 by means of fitting, soldering, partial screw-threading, or in any other suitable manner. The bottom 12 of the well 5 is formed with an upturned annular rim 13 which defines an inlet opening 14 for the entry of liquid from the receptacle 3, and forms a seat for a cooperating, concave valve or closure 15.

The top of the well is closed by a cup-washer or similar closure 16, which carries a percolator tube 17 providing the well outlet 18 through which the heated liquid from the well is discharged. This top closure is snugly fitted to the body portion 9 to seal the well, and is preferably detachably connected therewith, either by means of screw threads, latching means disposed across the top of the closure and casing 11, or in any other suitable manner, in order to permit the unitary removal of the percolator tube and connected valve means for the purpose of cleaning or repair.

The valve head 15 is detachably connected with a stem 19, either by means of a screw bolt cooperating with a bore in the enlarged end 20 of the stem or in any other suitable manner, which stem reciprocates in the percolator tube 17 and suitably limits the lateral movement of the valve head with respect to the valve seat 13.

The stem 19 is flat in shape and as thin as is compatible with giving it sufficient strength, in order to minimize obstruction to the flow of liquid through the outlet 18 and the percolator tube 17 into which the stem extends.

To prevent separation of the stem and valve head from the tube when the latter is lifted out, lateral projections 21 are provided at the upper end of the stem, which is formed in the shape of a flat T for that purpose, and a narrow, inwardly projecting shoulder 22 is spun or otherwise formed at the bottom edge of the tube. If desired, similar projections may be secured crosswise of the top of the T, as shown for example in Fig. 2.

The operation of the device is substantially as follows:—The hydrostatic pressure of the

head of water or other liquid in the receptacle 3 will continually tend to force the valve head 15 upwardly, and permit liquid to enter and fill the well.

5 When the pressure in the well is insufficient to resist this tendency, liquid will enter the well, substantially filling the same, and will then be rapidly heated and partially vaporized by the electric heating unit 6. The 10 pressure thereby created will serve to keep the valve head 15 in tight engagement with the seat 13, and the heated liquid will be forced to escape upwardly through the open outlet 18 and percolator tube 17, ultimately 15 rejoicing the major portion of liquid in the receptacle 3 in the well-known manner.

The pressure in the well will be reduced by reason of the discharge of the heated liquid and vapor through the percolator tube, and 20 when it finally reaches the point where it is insufficient to withstand the external pressure upon the valve head 15 exerted by the major body of liquid in the receptacle 3, the valve will be automatically lifted off the seat 13 and 25 a fresh portion of liquid will flow into the well for heating.

The construction and arrangement of parts embodied in the invention herein described provides a very effective and advantageous 30 valve-controlled heating well.

The location of inlet opening 14 at the bottom of the well, and in slightly spaced relationship from the bottom of the receptacle 3, assures continual application of the 25 heat to the coolest portion of the liquid in the percolator, where its application is most desirable. The provision of a single large inlet opening facilitates the inflow of liquid, and materially reduces the possibility of 40 sedimentation and obstruction favored by the use of small openings.

The construction and arrangement of the valve 15 renders it freely movable and responsive to the pressure control, and its connection with the removable top unit through 45 the medium of the percolator tube, renders it readily removable for cleaning or repair. It will be noted further, that this provision for removal specifically involves those parts 50 of the well construction which contain the most crevices and difficultly accessible parts, elements which present a considerable obstacle to cleaning or repair while they are in position in the percolator. Upon the removal 55 of this top unit however, all of these parts are brought within easy reach, and a practically unobstructed and accessible expanse of the body of the well is presented, which can be readily cleaned or otherwise treated in 60 situ.

All of the constituent elements of the top unit can be detachably assembled in the unit to permit complete disassembly if desired. For removal of the stem 19 with its enlarged head 65 21 from the percolator tube 17, for example,

provision may be made therefor, by making the bottom portion 23 of the tube 17 in a separate section from the upper part and connecting the two by a threaded coupling. The upper end of this bottom section when detached, will present an unrestricted opening through which the enlarged end 21 of the stem will readily pass, the valve head 15 first being detached from the other end of the stem.

In further reference to the stem 19, the flat configuration to minimize obstruction to the flow through the tube 17, may extend over the entire stem except for the provision of a bored button or enlargement 20 at the end 80 connected with the valve 15 where a screw bolt connection is used; or if desired, may be imparted only to the portion which extends into and slightly below the tube 17 when the valve 15 is resting upon the seat 13 as shown 85 in Fig. 1, in which position the principal flow of liquid through the percolator tube takes place.

Other changes and modifications may likewise be made as will be apparent to one skilled 90 in the art, without departing from the spirit of my invention.

While in the foregoing I have disclosed a preferred embodiment, it is to be understood that my invention is not limited thereto, but 95 contemplates all such equivalent constructions and arrangements of parts as may fall within the scope of the following claims.

I claim as my invention:

1. A percolator which comprises, a receptacle for liquid, a well within said receptacle adapted to contain a portion of said liquid, means disposed about the outside of said well for heating the liquid in said well, a valve-controlled inlet at the bottom of said well 100 for the introduction of said liquid thereinto, and outlet means in said well for the discharge of heated liquid therefrom.

2. A percolator which comprises, a receptacle for liquid, a well disposed within said receptacle adjacent but spaced from the bottom thereof and having an outlet and a bottom inlet, means for heating the liquid in said well, and means for periodically admitting liquid into said well through said bottom inlet and subsequently directing the effect of the pressure created by heating the liquid in said well to the discharge of the heated liquid through said outlet.

3. A percolator which comprises, a receptacle for liquid, a well within said receptacle adapted to be immersed in the liquid therein and having an inlet opening in the bottom thereof, means for heating the liquid in said well, automatically operated valve means adapted to periodically open and close said bottom inlet, and outlet means in said well for the vertical discharge of the heated liquid from said well.

4. A percolator which comprises, a recep-

- 5 tacle for liquid, a well within said receptacle, means for heating the liquid in said well, a valve seat at the bottom of said well defining an inlet thereto, an outlet tube at the top of said well for the heated liquid, and a displaceable valve adapted to contact with said seat to close said inlet, said valve being adapted to be displaced from contact with said seat for the entry of a fresh portion of liquid to be heated when the pressure within said well is reduced below the external pressure by the discharge of heated liquid through said outlet tube.
- 10 5. A percolator which comprises, a receptacle for liquid, a well within said receptacle adapted to contain a portion of said liquid, means for heating the liquid in said well, an outlet tube at the top of said well for the discharge of the heated liquid, a valve seat at the bottom of said well defining an inlet through which liquid enters the well, and a valve within said well adapted for vertical movement with respect to said seat to open or close said inlet, the position of said valve with respect to the opening or closing of said inlet being controlled by the pressure differential above and below said valve.
- 15 6. A percolator which comprises, a receptacle for liquid, a well disposed within said receptacle in adjacent but spaced relationship to the bottom thereof, a valve seat in the bottom of said well defining an inlet, a vertically displaceable valve adapted to cooperate with said seat to open or close said inlet, an outlet tube in the top of said well, and a guiding stem connected with said valve and extending into said outlet tube to limit the lateral movement of said valve with respect to said seat.
- 20 7. A percolator which comprises a receptacle for liquid, a well disposed within said receptacle and spaced from the bottom thereof, means for applying heat to the wall of said well, an outlet tube extending from the top of said well, a valve seat at the bottom of said well defining an inlet thereto, a valve adapted for vertically displaceable engagement with said seat to open or close said inlet, a stem projecting from said valve into said outlet tube and limiting the lateral movement of said valve with respect to said seat, a lateral projection upon the portion of said valve stem within said tube, and a shoulder projecting inwardly at the bottom edge of said tube adapted to cooperate with said projection to retain said stem within said tube.
- 25 8. A percolator which comprises, a receptacle for liquid, a cylindrical well disposed within said receptacle in adjacent but spaced relationship to the bottom thereof, heating means adjoining the wall of said well, an annular rim in the bottom of said well defining an inlet opening, an outlet tube at the top of said well, a vertically displaceable valve adapted to rest upon said rim in closing re-
- 20 9. A percolator which comprises, a receptacle for liquid, a well disposed in said receptacle in spaced relationship to the bottom thereof and adapted to be encompassed by the liquid in said receptacle, an annular rim in the bottom of said well defining an inlet opening, means for applying heat to said well to heat liquid therewith, an outlet tube extending from the top of said well for the discharge of the heated liquid therefrom, and a vertically displaceable concave valve for periodically opening and closing said inlet, said valve being automatically operated by the difference in pressure between the head of liquid in said receptacle and that created by the heating and discharging of liquid in said well.
- 25 10. A percolator which comprises, a receptacle for liquid, a well within said receptacle adapted to be immersed in the liquid therein, means for heating said well, an outlet tube at one end of said well for the discharge of the heated liquid therefrom, an inlet in the end of said well opposite said outlet tube, and a valve for periodically opening and closing said inlet.
- 30 11. A percolator which comprises, a receptacle for liquid, a well within said receptacle adapted to be immersed in the liquid therein having an inlet at one end thereof, means for applying heat to said well, an outlet tube at the end of said well opposite said inlet end, and a valve for opening and closing said inlet, the opening or closing of said inlet by said valve being automatically actuated by the pressure difference between the head of liquid in the receptacle and that created by heating and discharging the liquid in the well.
- 35 12. A percolator which comprises, a receptacle for liquid, a cylindrical well disposed within said receptacle and having the bottom thereof disposed adjacent but spaced from the bottom of said receptacle, an upwardly inclined annular rim in the bottom of said well defining an inlet thereto, an outlet tube at the top of said well for the discharge of liquid therefrom, a cup-shaped valve disposed within said well and adapted to be supported by and set within said rim to close said inlet, a stem connected with said valve and extending into said outlet tube, a lateral projection upon the portion of said stem within said tube, and a shoulder projecting inwardly at the bottom edge of said tube adapted to cooperate with said projection to retain said stem within said tube.
- 40 13. A percolator which comprises, a receptacle for liquid, a cylindrical member within

said receptacle having an opening in its bottom portion disposed adjacent but in spaced relationship to the bottom of said receptacle, a closure for the top of said member, a percolator tube mounted in said closure, a stem disposed within said tube and extending into said cylindrical member, a lateral projection upon the portion of said stem within said tube, a shoulder projecting inwardly at the bottom edge of said tube, and a valve connected with the end of said stem which extends into said cylindrical member, said valve being adapted to cooperate with the bottom of said member to open or close said opening.

15. 14. A percolator which comprises, a receptacle for liquid, a cylindrical member disposed within said receptacle with its bottom adjacent but in spaced relationship to the bottom of said receptacle, an annular rim in the bottom of said member defining an opening, a closure for the top of said member detachably attached thereto, a percolator tube mounted in said closure, a stem disposed within said tube and extending into said cylindrical member, a lateral projection upon the portion of said stem within said tube, a shoulder projecting inwardly at the bottom

edge of said tube, and a cup-shaped valve connected with the end of said stem which extends into said cylindrical member, said valve being adapted to be supported by and set within said rim to close said opening.

70

15. A percolator which comprises, a receptacle for liquid, a well having an inlet in the bottom thereof communicating with said receptacle and an outlet, means for heating said well, and a valve disposed at the bottom of said well for opening and closing said inlet, said valve being operated by the differential in pressure between the inside and outside of said well.

75

16. A percolator which comprises, a receptacle for liquid, a well having an inlet in the bottom thereof communicating with said receptacle and an outlet, means for heating said well, a valve disposed at the bottom of said well for opening and closing said inlet, said valve being operated by the differential in pressure between the inside and outside of said well, and means for retaining said valve in operative position with respect to said inlet.

80

In testimony whereof I affix my signature.
